UNITED STATES PATENT OFFICE.

GLENN R. SHAFFER AND ANDREW M. SHAFFER, OF BIG RUN, PENNSYLVANIA.

STEAM-BOILER FILLER.

1,162,408.

Specification of Letters Patent. Patented Nov. 30, 1915.

Application filed August 19, 1912. Serial No. 715,920.

To all whom it may concern:

Be it known that we, GLENN R. SHAFFER and ANDREW M. SHAFFER, citizens of the United States, residing at Big Run, in the county of Jefferson, State of Pennsylvania, have invented certain new and useful Improvements in Steam-Boiler Fillers; and we do hereby declare the following to be a full, clear, and exact description of the invention, such as will enable others skilled in the art to which it appertains to make and use the same.

This invention relates to steam boiler fillers.

15 The object of the invention resides in the provision of a device of the character named which will automatically regulate the supply of steam to the pump which supplies the boiler with water.

20 A further object of the invention resides in the provision of a device of this character which will be simple in construction, efficient in use and which may be installed at a comparatively small cost.

25 With the above and other objects in view the invention consists in the details of construction and in the arrangement and combination of parts to be hereinafter more fully described and particularly pointed out 30 in the appended claim.

In describing the invention in detail reference will be had to the accompanying drawings wherein like characters of reference denote corresponding parts in the several views, and in which—

Figure 1 is a transverse section through a boiler showing the invention applied and the parts in the position they would occupy when the water in the boiler is above a predetermined level and the supply of steam from the boiler to the pump cut off. Fig. 2 a view similar to Fig. 1 with the parts in the position they would occupy when the water in the boiler is below a predetermined level and steam from the boiler is being fed to the pump. Fig. 3 a section on the line 3—3 of Fig. 1. Fig. 4 a detail perspective view of the float valve employed in the device.

50 Referring to the drawings, 10 indicates a boiler of any preferred construction. Hung from the upper side of the boiler 10 and dis-

posed in the steam space of the latter are hanger beams 11. Suspended from the beams 11 is a tubular member 12 provided at its ends with reduced upper and lower extensions 13 and 14 respectively which form shoulders 12'. The outer ends of these extensions are open so as to afford communication between the interior of the boiler and the interior of the member 12 at each end of the latter. Communicating with the interior of the member 12 adjacent its upper end is a steam pipe 15 which extends exteriorly of the boiler and is adapted to supply steam to the pump not shown. Slidably mounted in the major portion of the member 12 and adapted to open and close communication between the pipe 15 and the interior of the member 12 is a float valve B. The valve is formed of a hollow cylindrical member having a bearing flange 16 at each end so as to reduce to a minimum the friction between the valve B and the member 12 during the movement of the former in the latter.

When the level of the water is as shown in Fig. 1 or higher the valve B will be buoyed up and maintained in the position shown in Fig. 1 so that no steam from the boiler will pass through the pipe 15 to the pump which supplies water to the boiler. As soon as the level of the water in the boiler falls below what is shown in Fig. 1 the valve B will fall by gravity to the position shown in Fig. 2 when steam will pass from the boiler through the pipe 15 to the pump and effect the operation of the latter until the water is again raised to the level shown in Fig. 1. As soon as the level of the water is thus raised the valve B will be buoyed up by the rise of water to the position shown in Fig. 1 and the supply of steam to the pump cut off.

What we claim is:—

The combination of a boiler, a bracket element depending from the top of the boiler within the latter, a tubular member supported by said bracket element and having its upper and lower ends reduced to form shoulders, the lower end of said tubular member extending below the normal level of the water in the boiler, a pipe having one end communicating with the interior of the

tubular member adjacent the upper shoulder and its other end disposed exteriorly of the boiler, and a hollow cylindrical float valve movable within the tubular member and held against the upper shoulder when the water in the boiler is at its normal level whereby communication between the tubular member and pipe is closed.

In testimony whereof, we affix our signatures in presence of two witnesses.

GLENN R. SHAFFER.
ANDREW M. SHAFFER.
